CORDED FLY OPENING FOR GARMENTS

Joseph Paul Gray, Frackville, Pa.

Application February 10, 1953, Serial No. 336,116

1 Claim. (Cl. 2—234)

This invention relates to a corded fly opening for garments.

The invention applies particularly to shorts for men and to dresses having side, front or back openings with a slide fastener closure of the type commonly known as a "zipper." It also applies to other garments in which a fly opening or the like is juxtaposed to a slide fastener closure.

The object of the invention is to provide a fly opening construction which cannot be caught in a slide fastener. It is common knowledge that from time to time the fly opening flap of an undergarment, say a pair of men's shorts, is caught in the slide fastener of a pair of trousers to the extent that the slide fastener is jammed in a certain position and can neither be opened or closed beyond that position. The present invention provides positive means in the fly opening flap of the shorts or other similar garment to prevent entrapping of said flap in the slide fastener of a pair of trousers or other outer garment.

Briefly, this invention consists of beading or cording the free edge of the outer flap of a fly opening in an undergarment such as a pair of men's shorts or a dress of the character above mentioned. This has the effect of increasing the thickness of the free edge of said flap without adding substantially to its degree or extent of stiffness. The thickened edge possesses body and the cloth of which it is made snugly encloses a core. Consequently, the cloth which forms said edge of the flap cannot itself engage the fastener elements of the slide fastener and the combination of said cloth and its inner core is too thick and too heavy to be caught therein. Consequently, a beaded or corded edge of the character described cannot possibly jam a slide fastener.

The core to which reference has above been made is simply a length of cord or twine which is sufficiently flexible to avoid rendering the garment flap uncomfortably stiff or rigid. A suitable material for this purpose is a braided cotton cord about one-eighth of an inch in diameter. This, however, is purely illustrative and other types of cord or twine may be used to advantage in connection with this invention.

An important feature of this invention is the usefulness of the corded fly opening flap for the purpose of locating the fly opening, especially in hot weather when the shorts are apt to twist or turn about the person. The corded edge of the outer fly opening flap is readily detected, and with it the fly opening itself.

A preferred form of this invention is shown in the accompanying drawing in which:

Fig. 1 is a front view of a pair of men's shorts having a beaded or corded fly opening flap made in accordance with this invention.

Fig. 2 is an enlarged fragmentary view of the fly opening construction of said pair of shorts, the outer flap of said fly opening being partly broken away to expose the inner cord which prevents it from being caught in a slide fastener.

2

Fig. 3 is a fragmentary transverse section through said fly opening construction, showing how the inner cord is secured within the edge of the outer flap of said fly opening.

The pair of shorts 10 which is shown in Fig. 1 of the drawing is intended to illustrate the various garments to which the present invention may be applied. For purposes of illustration, therefore, the invention will be described solely in terms of its relation to the garment shown in Fig. 1.

Garment 10 has a fly opening as the drawing clearly shows. The fly opening is formed between an inner flap 12 and an outer flap 14 which overlap each other in conventional manner. Inner flap 12 is conventional in construction as Fig. 3 clearly indicates. Outer flap 14 is also conventional in construction except for the fact that it embodies a core 16 which may be made of braided cotton cord or any other suitable cord or twine. Flap 14 has a free edge 18 which is rolled over core 16.

Stitches 20 parallel core 16 and lock said core within said rolled edge 18.

More specifically, outer flap 14 has an outer wall 22 and an inner wall 24 which receive core 16 between them. Edge 18 is the bight which joins said outer and inner walls 22 and 24 and it is within said bight that core 16 is held. Stitching 20 and also stitching 26 secure the two outer and inner walls together. Stitching 20, however, performs the additional function of retaining core 16 within bight 18 and drawing said bight snugly around said core.

It will be noted in Fig. 2 that core 16 extends substantially the full length of flap 14. More precisely, it extends substantially the full distance from that portion of the upper end of the outer flap which is secured to the upper end of the inner flap to that portion of the lower end of the outer flap which is secured to the lower end of the inner flap. Consequently, the entire edge 18 of outer flap 14, to the extent that said edge is free, is reinforced by core 16 so that no part of it can be caught in a slide fastener.

An important feature of this invention is the manner in which core 16 is fastened within edge or bight 18 to prevent displacement or dislodgment thereof. This is accomplished by stitching 20 holding said core within said bight and also by means of stitches 28 and 30 which extend transversely across the upper end of the core and thereby secure said upper end of the core to the upper end of the outer flap 14. As a matter of fact, the upper end of the core may project upwardly beyond the top end of the fly opening so that it may be secured not only to the outer flap but also to the inner flap. In such case, the very same stitching 28 and 30 which are conventionally applied to a garment, such as garment 10, above the fly opening would also be used to fasten the upper end of the core to the flaps of said fly opening.

The lower end of core 16 is not secured to the lower ends of the two fly opening flaps. Instead, it is completely free at the lower end of bight 18 except that it is confined therein by vertical or longitudinal stitching 20. This is important to properly secure core 16 to the outer flap of the fly opening without rendering the same rigid or otherwise inflexible. Attaching the core at only one end and confining it along its full length also compensates for unequal shrinkage as between the core and the cloth of which the flap is made and helps prevent the core from ruffling or tearing the cloth or tearing the stitching which secures the core to said flap.

The foregoing is illustrative of preferred forms of this invention and it will be clearly understood that this preferred form may be modified in many respects and

other preferred forms may be provided within the broad scope of the invention and of the claim.

I claim:

A corded fly opening for garments of the character described, comprising an outer flap and an inner flap, said flaps being in overlapping relation to each other and being secured to each other at both ends and free from each other intermediate their said ends, said outer flap having an outer and an inner wall joined by a bight extending longitudinally along the free edge of said outer flap between its two secured ends, said walls being also sewed together by stitching extending longitudinally thereof in spaced, parallel relation to said bight, a tunnel being thereby formed between said outer and inner walls and between said bight and said longitudinal stitching, and a cord disposed within said tunnel and extending longitudinally thereof, said cord extending substantially the full length of said tunnel and up to its upper end,

10

5

cross-stitching being applied across the upper end of the cord and the two walls of said outer flap to secure said upper end of the cord to the upper end of the outer flap and thereby to prevent downward displacement of said cord within its said tunnel, the major portion of the cord being disposed below said cross-stitching and being free to move within said tunnel and thereby to compensate for unequal shrinkage of said cord and said outer flap.
